FEEDING MECHANISM FOR SEWING MACHINES

John P. Weis and Frederick F. Zeier, Nyack, N. Y., assignors to Willcox & Gibbs Sewing Machine Company, New York, N. Y., a corporation of New York

Original application September 24, 1934, Serial No. 745,343. Divided and this application October 11, 1934, Serial No. 747,871

29 Claims. (Cl. 112—210)

The present invention relates to improvements in feeding mechanisms for sewing machines. This application is a division of our copending application Ser. No. 745,343, filed Sept. 24, 1934.

5 It is an object of the present invention to provide an improved feeding mechanism which will be simple in construction and which will be smooth and positive in its feeding action.

Features of the present invention in connection 10 with this object include the provision of sturdily supported feed lifter and rocker rods extending longitudinally of the machine from a thoroughly lubricated point within the trunk of the machine to a point at the opposite end of the machine close 15 to the feed dog and its main supporting parts.

A complementary feature includes novel short 20 driving connections between a main drive shaft and the lifter and rocker rods so that there is a minimum of inertia when operating the machine, even at very high speeds. The feeding mechanism of the present invention, associated with a centrally disposed main drive shaft, facilitates 25 manual manipulation when the operator desires to condition the needle, looper, and feeding mechanism.

It is another object of the present invention to provide a feeding mechanism having a wide margin of adjustability, so that a change-over from coarse to fine stitch feed may be easily and quickly made, and to do this without guessing.

Features in connection with this object include 30 the provision of a novel regulating mechanism whereby it is possible to change the feeding mechanism without replacing any of the parts and by merely turning a small regulating knob. This feature includes a simple mechanism for changing the pivot point in one of the levers of the feeding mechanism so that the extent of travel is varied, and accomplishes this through a novel interconnecting link mechanism.

A particularly novel feature is the provision of 35 a transparent indicator plate, preferably built into the base of the sewing machine, with a fully enclosed pointer aligning with a graduated scale on the indicator plate in a manner to closely indicate to the operator the exact number of stitches per inch.

Other objects, features, and advantages will appear hereinafter:

In the drawings:

Figure 1 is a sectional view taken longitudinally through the complete sewing machine of the present invention.

therin.

Fig. 9 is a detail view of the transparent stitch

indicator plate and scale.

The present invention is not limited to the details of construction and arrangement of parts illustrated in the accompanying drawings since the principles of the invention are capable of other embodiments and the phraseology employed is for the purpose of description and not for limitation.

Referring now in detail to the drawings, the 25 sewing machine of the present invention includes a frame 12 comprising a hollow trunk 13 for supporting a main driving mechanism 14, with a preferably hollow and integral upper arm 15 supporting a needle operating mechanism 16, and a 30 preferably integral lower arm 17 for supporting looper and feeding mechanisms 18 and 19 respectively and for forming a work support 20. In general it has a smooth outer finish for appearance, ease in cleaning, and elimination of all outward obstructions which would interfere with handling the work.

The hollowed trunk 13 comprises a front wall 21, rear wall 22 and side walls 23 and 24, the latter having large side openings 25 and 26 respectively to accommodate and support the main driving mechanism 14. Further, the trunk 13 is provided with a top opening 27 and a bottom opening 28 large enough to pass various operating parts and to receive the hands of a person making the original assembly or making subsequent repairs and adjustments. A cover plate 29 and a bottom plate 30 are provided for the top and bottom openings 27 and 28 respectively, and are held in place with screws 29' and 30' in the usual manner. End caps 31 and 32 are similarly held against the side walls 23 and 24 respectively by screws 31' and 32' to make a complete oil tight closure for the main operating parts. These openings and caps permit bench assembly of the 35 40 45 50 55

operating parts contained in the trunk of the machine and facilitate assembly thereof by making it possible to pass the main driving mechanism 14 or large sub-units thereof through the various openings. When the caps are secured thereto an effective seal is provided which prevents leakage of oil while the machine is in operation.

The main driving mechanism herein briefly disclosed and described is more completely disclosed and described in our copending application Serial No. 2,806, filed January 21, 1935.

The upper arm 15 is preferably made with a substantially hollow chamber 33 and may be of substantially rectangular and tapering cross section, with a transverse web 34 at the trunk end, and a similar transverse web 35 near a head 36 at the end of the arm, to support a main rock shaft 37 of the needle operating mechanism 16. The head is provided with suitable bearings 38 and 39 for a needle bar 40 and a presser bar 41, see Figs. 1 and 2, and is provided with a large opening 42 to facilitate adjustments and repairs to the parts therein. This opening is normally closed with a cover plate 43, held in place by screws 43', to cover up the working mechanism and to prevent adverse escape of oil.

The lower arm 17 is preferably made integral with the frame 12, with a front wall 44 and a rear wall 45 extending horizontally from the trunk 13 in a direction parallel to and underlying the upper arm 15. In order to make these walls rigid or sturdy at the outer extremities, and in order to provide suitable bearings for important operating parts, an end wall 46 is provided at their outer extremities and a shorter transverse web 47 is provided intermediate the end wall 46 and the sides of the walls 44, 45, and 23. Thus, the lower arm 17 provides a sturdy non-vibrating support for both the feed mechanism 19 and the looper mechanism 18, detailed description of which is given hereinafter.

The lower arm 17, is arranged to provide a work support 20 of a short height and width, and to provide a sturdy and quickly interchangeable support for a throat plate 49. Supporting lugs 50, 51, and 52, best seen in Fig. 5, are provided on the front wall 44 and associated rear lugs 53, 54, and 55, are provided on the rear wall 45 to form a support for the long and large area cloth plate 56, which may be secured thereto by screws 51 entering tapped holes 57', or may likewise support a small area cloth plate 58 indicated by dot-and-dash lines.

The cloth plates 56 and 58 are normally made of thick material for strength and rigidity and are provided with a cut-out 59, through their thickness, adapted to merely locate and not to support an adaptor 60 and the throat plate 49. As may best be seen in Figs. 1, 2, 3, 4, and 5, the lugs 50, 51, 53, and 54 are adapted to directly support the adaptor 60 and the throat plate 49, the latter being secured to the adaptor by screws 61 threaded into holes 61'. Interchangeable throat plates may be provided with various cut-outs to accommodate various stitching combinations, different widths of needle gauges for light and heavy work, and various feed dogs. The main purpose of the adaptor 60 is to make possible the use of a thick cloth plate 56 with relatively thin throat plates 49, both resting upon the same bosses and more particularly to form a clearance for loopers 62, and feed dog 63, see Figs. 1, 2, and 5.

It also forms a rigid support for the throat

plate to prevent deflection under heavy pressure from the needle when operating on heavy materials, and prevents deflection under heavy pressure of the presser foot. In addition, this arrangement of parts is such that the change over 5 from the wide cloth plate 56 to the narrow cloth plate 58, and in effect the change from a flat bed to a cylindrical machine, may be effected without disturbing the throat plate which is desirable when there is a critical adjustment between the throat plate, feed dogs, and the needle guide. Also, it is possible to remove or change the throat plate 49, without disturbing the cloth plate, when it is desired to make repairs, changes, or adjustments to the feed dog or loop forming 15 instrumentalities located in the lower arm 17.

The novel lower arm 17, interchangeable work supports 20, the ready interchangeability of the throat plates 49 without changing the cloth plates 56 or 58, briefly described herein, and a 20 novel needle guard and loop spreader associated therewith but not illustrated or described herein, form the subject matter of a continuation in part application Serial No. 750,259, filed October 27, 1934 and in our divisional application 25 Serial No. 185,886, filed January 20, 1938. Brief, rather than detailed description relative thereto has been given herein in order to facilitate describing and understanding of the novel feeding mechanism which forms the main subject 30 matter and claims of the present patent application.

The main driving mechanism 14 is described herein, in connection with only the transverse looper 62, illustrated in Figs. 1 through 5, although the novel feeding mechanism of the present application is equally applicable for use with the longitudinal and universal type loopers fully illustrated and described in the aforementioned application of which this is a division. It comprises a main drive shaft 64 with cranks A, B, C, D, and E, and each preferably formed in the shape of a ball, as shown in Fig. 7 accommodating main driving connections including crank arms 65, 66, 67, 68, and 69 respectively provided with ball and socket connections 70, 71, 72, 73, and 74 (see Fig. 1) in order to allow the crank arms to rotate relative to the balls and to permit slight vertical displacement to compensate for slight irregularities in the location of those parts which connect with and are operated by the other end of the crank arms. Integral plates 75 reinforce the main drive shaft 64 between the individual cranks.

The crank arms 65-69 are preferably provided with ball and socket and like connections 76, 77, 78, 79, and 80 respectively for connection to an arm 81, bell crank 82, arms 83 and 84, and link 85, at their ends opposite the main drive shaft, for driving the needle operating and other mechanisms all in a manner about to be described.

The main drive shaft 64 together with the main driving connections 14 including the crank arms and associated ball and socket connections, 65 bell cranks, and arms just described may be assembled extraneously of the frame and may then be passed through the side wall opening 26 into the chamber 13' of the hollow trunk 13 for assembly. These assembled parts, just described 70 in detail, are tilted slightly and the crank arms are moved into the chamber whereupon the main shaft may again be moved into a horizontal plane substantially central of the side wall openings 25 and 26 where it is supported by 75

bearings 86 and 87 and held in place by the caps 31 and 32. A main drive pulley 88, is secured to the outer end of the shaft 64 by a set screw 88' and a handwheel 89 may be made integral therewith or may, as shown, be secured to a shoulder on the pulley with one or more screws.

This centrally located main drive shaft 64 brings the handwheel 89 into a location where it may be very conveniently grasped without danger of skinning knuckles as occurs sometimes when the handwheel is close to the base of the machine, and without danger of awkward twisting of the arm as is required when the hand wheel is on the front of the machine. Further, and of particular importance, it makes possible the use of short crank arms to the various mechanisms, thereby overcoming vibration and inertia of moving parts to a very marked extent. This latter factor is enhanced by having the main drive shaft parallel the rocking and reciprocating rods of the various associated mechanisms. All of these advantages will be more apparent after the individual mechanisms are described.

The needle driving mechanism 16 comprises the rocker rod 37 journaled in bearings 34' and 35' in the walls 34 and 35 respectively, with an arm 81 secured to the trunk end thereof by a yoke 81' and having a bearing stud 90 at its outer end connecting with the ball and socket connection 76 at the upper end of the crank arm 65. At the head 36 end of the arm 15 the rocker rod 37 is provided with a needle driving arm 91 adjustably secured thereto by two screws 91' for adjusting the height of the needle 93 relative to the looper 62. This arm is connected to a hollow needle bar 40 through a double link 92 and link pin connections 92' (see Fig. 2). At its lower end the needle bar is adapted to interchangeably receive various types of needles 93 in the conventional manner.

As may be seen best in Figs. 2 and 4, a stud 94 is provided with a finger 95 extending through an opening 95' at the front of the head, and exteriorly of the latter is provided with a thread carrying eyelet 96. This finger is in the form of a slide adapted to ride between plates secured to the head 36 in spaced relation. This latter structure insures a sturdy driving action between the arm 91 and the needle bar 40 and also insures an efficient drive for the thread carrying eyelet 96 which forms a slack for the formation of succeeding stitches. One vertical reciprocation of the needle downward and upward by the crank arm 65 is accomplished each time the crank on the main drive shaft 64 is given a complete revolution.

As shown in Figs. 1 through 5 particularly, the looper mechanism 18 includes a looper carrier 97 having a pivot connection 98 projecting from a collar 99. The looper carrier 97 is provided with a hole 100 adapted to receive a looper 62 having a thread carrying and needle hook engaging blade 101, held therein by a screw 102. Various types and shapes of loopers, depending upon the stitch formation desired, may be supported in the one carrier in this manner.

The collar 99 is rotatable on an upper rod 103, the latter being supported for reciprocatory movement in bearings 104 in the trunk and in the lower arm 17. The collar is held against axial movement thereon by thrust collars 105 after the looper 62 is properly located with respect to the needle 93. Spacing between the collars 105 is just enough to prevent adverse axial movement of the collar 99 on the upper rod 103,

yet sufficient to permit a free rotating or rocking movement thereof on the rod.

In order to move the looper 62 relative to the needle in an elliptical path in the usual and well known manner to form a Federal Standard 5 Stitch Style 401, the looper carrier 97 is provided with a double pivot connection 98 and 106 to upper and lower rods 103 and 107 respectively provided with driving connections 109 and 110, see Figs. 1 through 5. The connection 109 for the 10 upper rod 103 includes the crank arm 66 having the ball and socket connection 71 with the crank B on the main drive shaft 64 and with a ball and socket connection 71 to the bell crank 82 pivotally mounted on a cross shaft 111, the bell 15 crank having a ball and socket connection 112.

The main connection 110 for the lower rocker rod 107 includes the crank arm 67 having the ball and socket connection 72 with the crank C on the main drive shaft 64 and having a ball and socket 20 connection 73 to the front end of the arm 83 secured to the lower rocker rod.

Reciprocation of the upper rod 103 moves the looper 62 from the solid line to the dot-and-dash line position and vice versa, shown in Fig. 1, and 25 rocking movement of the lower rod, 107 moves the looper from solid line to the dot-and-dash line position shown in Fig. 2, all in timed relation with reciprocation of the needle 93. The lower rocker rod 107 is held in desired position lengthwise of the bed by collars 108' engaging bearings 108. The upper rod 103, however, is not held against endwise movement since it must be reciprocated in the bearings 104 in order to impart 30 rocking movement to the looper carrier 97. 35

Since there is only a comparatively short crank arm connection between the cranks and the upper rod and lower rod, very little inertia is developed so that the parts may be operated at a very high speed. This operating advantage is also enhanced by having the main drive shaft parallel the upper rod and lower rocking rod since a comparatively straight connection is provided between the crank on the main drive shaft and the bell crank connection to the upper rod, and a 45 similar comparatively straight main connection is provided between the lower rocker rod and the main drive shaft.

The feeding mechanism 19 for moving materials through the machine and forming the main subject matter of this application and the appended claims comprises a feed rocker rod 114 and a feed lifter rod 115 mounted in suitable bearings in the lower arm 17 and trunk 13. This mechanism is best seen in Figs. 2 and 5. It comprises a feed dog 63 secured to a feed dog carrier 116 as by screws 117, and this carrier in turn is connected to an arm 118 adjustably clamped to the rock shaft 114 by a split clamp construction 119 through a spring 120 under screws 121 and 60 at its other end has a connection through a flat spring 122 and coil spring 123 to an arm 124 having a yoke connection 125 to the feed lift rod 115. 55

The feed dog 63 passes through suitable apertures 126 in the throat plate 49 in the usual manner and is given a four-motion movement through timed rocking of the feed rock rod 114 and feed lift rod 115. Any suitable feed dog, depending upon material and stitch requirements, may be 70 secured to the carrier as by the screws 117. Co-operating with the feed dog 63 is a presser foot 127 carried by the presser bar 41, which is tubular and operates in the bushing 39 in the head 36 in the well known manner. 75

A connection 128, see Figs. 1, 3, 4, 5, including an arm 129 connected by a yoke 130 between the feed lift rod 115 and a ball and socket connection 79 to the lower end of the crank arm 68 is provided to rock the feed lift rod. Thus, each time the crank D is given one complete turn the lower end of the arm 124, see Fig. 5, is oscillated a predetermined extent and the spring 122 at the end thereof lifts the feed dog 63 from a position below the throat plate 49 to a position level with the top thereof or slightly above it to grip the materials between it and the presser foot 127.

Operation and adjustment of the feed rocker rod 114 which controls the extent of feed, is accomplished in an advantageous manner with a novel adjusting mechanism 132 provided by the present invention. This mechanism is best illustrated in Figs. 6 through 9 and comprises an arm 133 secured to the trunk end of the operating rod 114 and having a link 85 connection through pivot studs 80 and 134 to the crank arm 69 with a ball and socket connection 74 to the crank E of the main drive shaft 64.

As may best be seen in Fig. 6, the crank arm 69 is moved pivotally about a bearing block 135 having a pivot pin connection 136 with a sliding finger 137 so that as the top end of the crank arm 69 is driven by the crank 64 in a direction to the left of the vertical centerline of the drive shaft, the upper end of the crank arm is moved to the left above the pivot pin 136 and the lower end thereof moves to the right of the centerline and simultaneously pulls the link 85 and arm 133 to the right as viewed therein in order to move the rocker rod 114 in a clockwise direction, and vice versa when the main drive shaft 64 moves the top end of the crank arm to the right of the vertical centerline.

The bearing or pivot block 135 is movable vertically in a channel 138, formed by a notch 139, and plate 140, the latter being held in place by suitable bolts 141, and is moved vertically in the channel by the sliding finger 137 into any desired station. A sleeve 143, secured in lugs 144 and 145 integral with the side wall 24 of the trunk 13, is provided with a hollow chamber 146 to accommodate a feed or adjusting screw 147 supported in bearing sleeves 148 and 149 at the lower end with a special bearing sleeve 150 located in an upper lug 151 with a set screw 152. A pair of thrust collars 153, secured to the adjusting screw 147 with set screws 154 at opposite ends of the upper bearing 150 permits rotation of the screw and at the same time prevents axial movement thereof.

The upper end of the adjusting screw 147 is provided with a slotted head 155 adapted to accommodate a key 156, the latter being removable by the proprietor so that the stitches per inch cannot be varied by the operator in order to make a coarser stitch and quicker output, to increase his or her pay. Thus, the non-axially movable screw, and the frame advantageously locate and support a short key.

More intricate key shapes may be provided for the same purpose. Near the lower end of the sleeve there is provided a cut-out 157 adapted to clear a feed nut 158 secured to the sliding finger 137 as by pins 159 and adapted to mesh with the adjusting screw 147 in order to move the finger and pivot block 135 downwardly when rotated in one direction and to move these parts upwardly when rotated in the other direction. When the screw and feed nut are adjusted to

locate and support the block in the upper position in the chamber 138, the lower end of the crank arm 69 is given a considerable oscillating movement, thereby imparting a large extent of rocking movement to the associated rocker rod 114 and considerable feeding movement to the feed dog 63 to form few stitches, for example 8 or 10 stitches per inch. However, when the parts are adjusted so that the block is in the lowered position relative to the chamber, the lower end of the crank arm is given the relatively smaller oscillating movement so that a proportionally smaller rocking movement is given to the rocker rod and the associated feed dog to form many stitches, e. g. 18 or 20 stitches per inch.

A novel gauge 160 is provided to clearly indicate the extent of feed and the exact number of stitches per inch formed by the various adjustments. This gauge comprises a pointer 161 in the form of an L shaped strip attached to the feed nut 158 portion of the sliding finger 137 by a screw 162 with a pointer 163 thereof adjacent a transparent plate 164 as best seen in Figs. 6 and 9, in the front wall 21 of the trunk 13. When it is desired to form ten stitches per inch, the key is turned until the pointer aligns with the numeral and line ten of a scale on the transparent plate, and when it is desired to form twenty stitches per inch, the adjusting screw is turned around by the key until the pointer is aligned with the number and line twenty on the scale. Thus, guess work is entirely eliminated and a positive indication is given to the operator and supervisor relative to the setting of the stitch for various types of work.

The finger 161 of the gauge 160 provided by the present invention may be passed outwardly of the frame 12 through any suitable slot and aligned exteriorly with the graduations on the plate 164. However, the illustrated embodiment is much more advantageous because, through the transparent plate and associated arrangement of parts, it is possible to retain the advantage of a fully enclosed oil chamber 13 (a line 166 in the transparent plate also indicates oil level) and because it has the advantage of preventing the finger 161 and pointer 163 from catching the work, the operator, or his clothes. Also, the pointer 161 may be made in various shapes, for example, in the form of a novel or round ring to encircle graduations, if preferred; the sharp straight line form now shown being merely illustrative of the present preferred form.

The fully enclosed oil chamber 13 with oil level indicating glass, and the other lubricating mechanism disclosed in the present drawings are more completely disclosed in our copending application Serial No. 755,372, filed November 30, 1934.

Thus, the present invention provides a smooth, efficient, and adjustable feeding mechanism for imparting a four motion movement to the feed dog. Further, this is preferably accomplished from a main drive shaft located midway in the trunk and parallel with main operating rods, as illustrated and described herein, but it should be understood that the structural details of the novel feeding mechanism of the present invention may also be associated with a main drive shaft located either in the upper or lower arms of usual sewing machines. The feed dog 63 and feed dog carrier 116 may be made in one piece if preferred, but to facilitate changing from wide to narrow feed dogs, and vice versa, is made separable as shown.

Other variations and modifications may be

made within the scope of the present invention and portions of the improvements may be used without others.

Having thus explained the nature of this invention and described a way of constructing and using the same, although without attempting to set forth all of the forms in which it may be made, or all of the modes of its use, we claim:

1. In a sewing machine the combination of a frame; a trunk in said frame; a transparent plate with graduations, carried by said trunk; a feed dog; a main drive shaft; means associated with said main drive shaft for actuating and for varying the extent of feeding movement of the feed dog; and a pointer carried by said means within said trunk, aligned with and movable past the graduations on the transparent plate for indicating the extent of feed.

2. In a sewing machine the combination of a frame; an oil chamber in said frame; a transparent plate with graduations, carried by said oil chamber, and through which the oil may be viewed and the level thereof checked; a main drive shaft; a feed dog; means associated with said main drive shaft for actuating, and for varying the extent of, feeding movement of the feed dog; and a pointer within said oil chamber associated with said means and movable thereby past graduations on the transparent plate for indicating the extent of feed.

3. In a sewing machine the combination of a frame; a transparent plate with graduations, carried by said frame; a feed dog; a main drive shaft; means associated with said main drive shaft for actuating and for varying the extent of feeding movement of the feed dog; and a pointer carried by said means within said frame, aligned with and movable past graduations on the transparent plate for indicating the extent of feed.

4. In a sewing machine the combination of a frame; a trunk in said frame; a lower arm; an upper arm; a needle operating mechanism in the upper arm; a looper; looper operating rods in the lower arm; means for operating the looper; a main drive shaft located in the trunk substantially centrally between the upper and lower arms; a feed dog; a feed rock rod; a feed lift rod, said feed dog and feed rods being located and supported in the lower arm, and separated from the looper operating rods; a crank arm associated with said main drive shaft and said needle operating mechanism; and means including a pair of crank arms associated with said centrally located drive shaft adapted to operate the feed dog through the feed lift and rock rods coordinately with the needle operating mechanism.

5. In a sewing machine the combination of a frame; a trunk in said frame; a lower arm; an upper arm; a needle operating mechanism in the upper arm; a main drive shaft located in the trunk substantially centrally between the upper and lower arms; a feed dog adapted to move work transversely across the lower arm; a feed lift rod; a feed rock rod, said feed rock and feed lift rod being located and supported in the lower arm; a crank arm associated with said main drive shaft and said needle operating mechanism; and adjustable means including a pair of crank arms adapted to operate the feed dog through the feed lift and rock rods, transversely of the lower arm and coordinately with the needle operating mechanism.

6. In a sewing machine the combination of a frame; a trunk in said frame; a lower arm; an upper arm; a needle operating mechanism in the

upper arm; a main drive shaft located in the trunk substantially centrally between the upper and lower arms; a feed dog adapted to feed work transversely of the lower arm; a feed lift rod; a feed rock rod, said feed dog and the feed rock and feed lift rods being located and supported in the lower arm; a crank arm associated with said main drive shaft and said needle operating mechanism; adjustable means including a pair of crank arms adapted to operate the feed dog through the feed lift and rock rods, transversely of the lower arm and coordinately with the needle operating mechanism; and a gauge associated with the last named means giving a visual indication of the extent of feeding.

7. In a sewing mechanism the combination of a work support; a main drive shaft; a crank on said main drive shaft; a feed dog; a feed dog carrier beneath the work support; means for lifting the feed dog; a feed rocker rod associated with the feed dog carrier; an arm on said rocker rod; a crank arm having a direct connection with said crank on said main drive shaft; a pivot for said crank arm intermediate its length; and a link directly connected to said crank arm at a point spaced longitudinally of the latter from said pivot, connecting said crank arm to said arm on the rocker rod for imparting feeding movement to the associated feed dog carrier coordinately with the lifting movement thereof.

8. In a sewing mechanism the combination of a work support; a main drive shaft; a crank on said main drive shaft; a feed dog; a feed dog carrier beneath the work support; means actuated by said main drive shaft for lifting the feed dog; a feed rocker rod associated with the feed dog carrier; an arm on said rocker rod; a crank arm having a direct connection to the crank of said main drive shaft; a pivot for said crank arm intermediate its length; a link connecting said crank arm to said arm on the rocker rod for imparting feeding movement to the associated feed dog carrier coordinately with the lifting movement thereof; and an adjustable support for said pivot adapted to vary the extent of movement of the end of the crank arm while the main drive shaft end does not vary, thereby changing the extent of associated rocker rod and feed dog carrier movement and extent of feeding movement.

9. In a sewing machine the combination of a frame; a main drive shaft in the frame; a feed dog; a feed dog carrier; means actuated by the main drive shaft for lifting the feed dog; a feed rocker rod associated with the feed dog carrier; an arm on said rocker rod; a crank arm on said main drive shaft, having a channel; a link connecting said crank arm to said arm on the rocker rod; a pivot for said crank arm; and adjustable means adapted to move said pivot in the channel of the crank arm to vary the extent of movement to the end of the crank arm and through the link vary the extent of feeding movement to the feed dog.

10. In a sewing machine the combination of a frame; a main drive shaft in the frame; a feed dog; a feed dog carrier; means actuated by the main drive shaft for lifting the feed dog; a feed rocker rod associated with the feed dog carrier; an arm on said rocker rod; a crank arm on said main drive shaft, having a channel; a link connecting said crank arm to said arm on the rocker rod; a pivot for said crank arm; adjustable means adapted to move said pivot in the channel of the crank arm to vary the extent of movement to the feed dog.

the end of the crank arm and through the link vary the extent of feeding movement to the feed dog; and a gauge associated with said means adapted to indicate the extent of feeding movement.

- 5 11. In a sewing machine the combination of a frame; a main drive shaft in the frame; a feed dog; a feed dog carrier; means actuated by the main drive shaft for lifting the feed dog; a feed 5
10 rocker rod associated with the feed dog carrier; an arm on said rocker rod; a crank arm on said main drive shaft, having a channel; a link connecting said crank arm to said arm on the rocker rod; a pivot for said crank arm; adjustable means 15
15 adapted to move said pivot in the channel of the crank arm to vary the extent of movement to the end of the crank arm and through the link vary the extent of feeding movement to the feed dog; a transparent plate with graduations; and a 20
20 pointer carried by said means behind said plate and cooperating with the graduations on the transparent plate to indicate the extent of feed.
12. In a sewing machine the combination of a frame; a main drive shaft in the frame; a feed 25
25 dog; a feed dog carrier; means actuated by the main drive shaft for lifting the feed dog; a feed rocker rod associated with the feed dog carrier; an arm on said rocker rod; a crank arm on said main drive shaft, having a channel; a link connecting said crank arm to said arm on the rocker rod; a pivot for said crank arm; adjustable means 30
30 adapted to move said pivot in the channel of the crank arm to vary the extent of movement to the end of the crank arm and through the link vary 35
35 the extent of feeding movement to the feed dog; a plate with graduations; and a pointer carried by said means and cooperating with the graduations on the plate to indicate the extent of feed.
13. In a sewing machine the combination of a frame; a feed dog; means for lifting the feed 40
40 dog; a feed rocker rod associated with the feed dog; an arm on the feed rocker rod; a main drive shaft in said frame; a crank arm on said drive shaft; a link connecting said crank arm to said arm on the rocker rod; a pivot for said 45
45 crank arm; a slide for said pivot; and a screw, supported for rotation and against longitudinal movement in said frame, and cooperating with said slide to vary the location of the pivot and to thereby vary the extent of feeding movement 50
50 to the feed dog.
14. In a sewing machine the combination of a frame; a feed dog; a main drive shaft; means associated with the drive shaft for operating said feed dog; adjusting mechanism in said means for controlling the extent of feeding travel of said feed dog; a screw in said adjusting mechanism, supported for rotation and against vertical movement in said frame; and an adjusting key located and supported for rotation and against axial movement by said screw and frame.
15. In a sewing machine the combination of a frame; a trunk in said frame; a transparent plate, carried by said trunk; a feed dog; a main drive shaft; means associated with said main drive shaft for actuating and varying the extent of feeding movement of the feed dog; and relatively movable means associated with said transparent plate and the first named means for indicating the extent of feed.
16. In a sewing machine the combination of a frame; an oil chamber in said frame; a main drive shaft; a feed dog; means associated with said main drive shaft for actuating, and varying the extent of feeding movement of the feed 75
75
- dog; a transparent plate enclosing said means, and through which the oil in the chamber may be viewed and the oil level checked; and relatively movable means associated with said transparent plate and the first named means for indicating the extent of feed.
17. In a sewing machine the combination of a frame; a transparent plate carried by said frame; a feed dog; a main drive shaft; means associated with the main drive shaft for actuating, and for varying the extent of, feeding movement of the feed dog; and relatively movable means associated with said transparent plate and the first named means for indicating the extent of feed.
18. In a sewing machine the combination of a frame; a transparent plate carried by said frame; a feed dog; a main drive shaft; means associated with the main drive shaft for actuating, and for varying the extent of, feeding movement of the feed dog; and a member movable by said means, enclosed by and viewable through the transparent plate, for indicating the extent of feeding movement.
19. In a sewing machine the combination of a frame; an oil chamber in said frame; a transparent plate carried by said oil chamber; graduations on said plate to indicate extents of feed; a line on said transparent plate for indicating the oil level; a main drive shaft; a feed dog; means associated with said main drive shaft for actuating, and for varying the extent of, feeding movement of the feed dog; and a pointer within said oil chamber associated with said means and movable thereby past the graduations on the transparent plate for indicating the extent of feed.
20. In a sewing machine the combination of a frame having a socket; a transparent plate with graduations, carried by said frame; a feed dog; a main drive shaft; means associated with said main drive shaft for actuating and for varying the extent of feeding movement of the feed dog, substantially enclosed and made inaccessible by said frame; a pointer carried by said means within said frame, aligned with and movable past graduations on the transparent plate for indicating the extent of feed; and a key adapted to be passed into the socket in said frame for association with, and to adjust, said means.
21. In a sewing machine the combination of a frame; a transparent plate carried by said frame; a feed dog; a main drive shaft; means associated with the main drive shaft for actuating and for varying the extent of feeding movement of the feed dog, substantially enclosed and made inaccessible by said frame; a member movable by said means enclosed by and viewable through the transparent plate, for indicating the extent of feeding movement; and a key adapted to be passed into said frame for association with and to adjust, said means.
22. In a sewing machine the combination of a frame; a trunk in said frame; a lower arm; an upper arm; a needle operating mechanism in the upper arm; a looper; looper operating rods in the lower arm; means for operating the looper; a main drive shaft located in the trunk substantially centrally between the upper and lower arms; a feed dog; a feed rock rod; a feed lift rod, said feed dog and feed rods being located and supported in the lower arm, and separated from the looper operating rods; a crank arm associated with said main drive shaft and said needle operating mechanism; means including a pair of crank arms associated with said centrally 70
70
- 75

located drive shaft adapted to operate the feed dog through the feed lift and rock rods coordinately with the needle operating mechanism; and a movable member associated with said means for indicating the extent of feeding movement.

23. In a sewing machine the combination of a frame; a trunk in said frame; a lower arm; an upper arm; a needle operating mechanism in the upper arm; a main drive shaft located in the trunk substantially centrally between the upper and lower arms; a feed dog adapted to move work transversely across the lower arm; a feed lift rod; a feed rock rod; said feed rock rod and feed lift rod being located and supported in the lower arm; a crank arm associated with said main drive shaft and said needle operating mechanism; adjustable means including a pair of crank arms adapted to operate the feed dog through the feed lift and rock rods, transversely of the lower arm and coordinately with the needle operating mechanism; and a movable member associated with said means for indicating the extent of feeding movement.

24. In a sewing machine the combination of a frame; a feed dog; means of lifting the feed dog; a feed rocker rod associated with the feed dog; an arm on the feed rocker rod; a main drive shaft in said frame; a crank arm on said drive shaft; a link connecting said crank arm to said arm on the rocker rod; a pivot for said crank arm; a slide for said pivot; a screw, supported for rotation and against longitudinal movement in said frame, and co-operating with said slide to vary the location of the pivot and to thereby vary the extent of feeding movement to the feed dog; a transparent plate with graduations in said frame; and a pointer associated with said slide and graduations, to indicate the extent of feeding movement.

25. In a sewing machine the combination of a frame; a feed dog; means of lifting the feed dog; a feed rocker rod associated with the feed dog; an arm on the feed rocker rod; a main drive shaft in said frame; a crank arm on said drive shaft; a link connecting said crank arm to said arm on the rocker rod; a pivot for said crank arm; a slide for said pivot; a screw, supported for rotation and against longitudinal movement in said frame, and co-operating with said slide to vary the location of the pivot and to thereby vary the extent of feeding movement to the feed dog; and a pair of relatively movable members associated with said slide, to indicate the extent of feeding movement.

26. In a sewing machine the combination of a frame; an oil retaining chamber in said frame; a main drive shaft; a feed dog; means associated

with the drive shaft for actuating the feed dog; adjusting mechanism within the chamber for varying the extent of feeding movement; and relatively movable means associated with said oil retaining chamber and the adjusting mechanism within the chamber for indicating the extent of feed.

27. In a sewing mechanism the combination of a work support; a main drive shaft; a feed dog; a feed dog carrier beneath the work support; means actuated by said main drive shaft for lifting the feed dog; a feed rocker rod associated with the feed dog carrier; an arm on said rocker rod; a crank arm having an upper end on said main drive shaft; a pivot for said crank arm intermediate its length; a link connecting the lower end of said crank arm to said arm on the rocker rod for imparting feeding movement to the associated feed dog carrier coordinately with the lifting movement thereof; an adjustable support for said pivot adapted to vary the extent of movement of the lower end of the crank arm while extent of movement of the upper and main drive shaft and thereof does not vary, thereby changing the extent of associated rocker rod and feed dog carrier movement and extent of feeding movement; a transparent plate with graduations; and a pointer associated with said adjustable support and movable thereby past the graduations on the plate, for indicating the extent of feed.

28. In a sewing machine the combination of a frame; graduations on said frame; a feeding mechanism; only one means including a screw for setting the feeding mechanism and for controlling the extent of feed; only one manually operable member in said last named means for operating it and the screw therein; and a pointer associated with said graduations and located remotely from said manually operable member for automatically indicating the setting effected by the first named means.

29. In a sewing machine the combination of a frame; graduations on said frame; a drive shaft; a feeding mechanism including a slideable pivot; only one means including a screw for sliding the pivot relative to the drive shaft, for setting the feeding mechanism and for controlling the extent of feed; only one manually operable member for operating the last named means and the screw therein; and a pointer located remotely from said manually operable member, associated with the graduations, and relative movement between said pointer and graduations being effected by said screw.

JOHN P. WEIS.

FREDERICK F. ZEIER.
